UNITED STATES PATENT OFFICE.

SOLOMON M. STEVENS, OF SULPHUR, OKLAHOMA.

SHADE AND CURTAIN HANGER.

1,266,078.

Specification of Letters Patent. Patented May 14, 1918.

Application filed November 21, 1917. Serial No. 203,180.

To all whom it may concern:

- Be it known that I, SOLOMON M. STEVENS, a citizen of the United States, residing at Sulphur, in the county of Murray, and 5 State of Oklahoma, have invented certain new and useful Improvements in Shade and Curtain Hangers, of which the following is a specification, reference being had to the accompanying drawings.
- 10 This invention relates to certain improvements in shade and curtain hangers and it is an object of the invention to provide a device of this general character having novel and improved means whereby it may be 15 readily and conveniently applied in position and whereby defacing of the window casing or other support is substantially eliminated. It is also an object of the invention to provide a novel and improved shade and 20 curtain hanger which comprises a base member and a bracket member slidably engaged with the base member together with coacting means carried by the base member and the bracket for maintaining the same in as- 25 sembled relation when the base member is in applied position upon a window casing or the like.

The invention consists in the details of construction and in the combination and ar- 30 rangement of the several parts of my im- proved shade and curtain hanger whereby certain important advantages are attained and the device is rendered simpler, less ex- pensive and otherwise more convenient and 35 advantageous for use, all as will be herein- after more fully set forth.

The novel features of the invention will hereinafter be definitely claimed.

In order that my invention may be the 40 better understood, I will now proceed to describe the same with reference to the accompanying drawing, wherein—

Figure 1 is a view in elevation of the upper portion of a window casing showing a 45 pair of shade and curtain hangers constructed in accordance with an embodiment of my invention applied thereto;

Fig. 2 is an enlarged sectional view taken substantially on the line 2—2 of Fig. 1;

50 Fig. 3 is an enlarged sectional view taken substantially on the line 3—3 of Fig. 1; and

Fig. 4 is an enlarged horizontal sectional view taken through the casing with a shade and curtain hanger applied thereto and 55 shown in top plan.

As disclosed in the accompanying draw-

ings, C denotes a window casing or other support and secured to the upper end portions of the sides of the casing are the base members B and with which coact the bracket 60 members M. Each of the base members B comprises a bar 1 of a length in excess of the width of the coacting side of the window casing and the opposite ends of the bar 1 are provided with the inwardly directed 65 extensions or arms 2 adapted to overlie the vertical faces of the side of the casing C. When in applied position, one of the extensions or arms 2 contacts with the outer vertical edge of the casing and in contact with 70 the second vertical edge is the threaded shank 3, directed through the second extension or arm 2 whereby the base member B is effectively held in applied position but capable of ready removal when desired. 75

The lower longitudinal margin of the bar 1 is defined by the inwardly disposed flange or lip 4 extending the entire length of the bar 1 between the extensions or arms 2. The inner face of the bar 1 immediately 80 adjacent the flange 4 is provided with the channel or groove 5 also extending the entire distance between the extensions or arms 2.

Each of the bracket members M includes 85 a base portion 6 snugly insertable between the bar 1 and the casing C and said portion 6 is provided with a forwardly offset portion 7 fitting within the channel or groove 5. By this arrangement the bracket 90 member M is capable of sliding movement longitudinally of the bar but is effectively held against displacement when the hanger is in applied position.

The bracket member M is provided with 95 the forwardly directed arms 8. One of said arms 8 is provided, as at 9, with means for engaging a shade roller while the second arm 8 is provided, as at 10, with means for supporting a curtain rod or pole. In the 100 present embodiment of my invention the bracket member M is shown as being formed of a single length of wire of requisite gage although it is to be understood that the bracket member may be of any construction 105 which embodies the specific features hereinbefore referred to.

I claim:

A device of the character described comprising, in combination with a support, a 110 bar adapted to be disposed across the support and provided with securing means, a

longitudinal margin of the bar being defined with an inwardly directed flange adapted to contact with the support, and a bracket member having a base portion snugly insertible between the bar and the support when in applied position, the inner face of the bar adjacent the flange being provided with a longitudinally directed groove, the base portion of the bracket being provided with a forwardly directed offset seatable within said groove, the bracket

being adjustable to different positions longitudinally of the bar when the bar and bracket are in applied position upon the support.

15

In testimony whereof I hereunto affix my signature in the presence of two witnesses.

SOLOMON M. STEVENS.

Witnesses:

T. F. GAFFORD,
R. P. SHORT.
